UNITED STATES PATENT OFFICE.

WILLIAM BARTHOLOMEW, OF CHICAGO, ILLINOIS, ASSIGNOR TO TROY LAUNDRY MACHINERY COMPANY, LIMITED, OF CHICAGO, ILLINOIS, A CORPORATION OF NEW YORK.

CENTRIFUGAL EXTRACTOR.

1,151,992.

Specification of Letters Patent. Patented Aug. 31, 1915.

Application filed March 26, 1912. Serial No. 686,404.

To all whom it may concern:

Be it known that I, WILLIAM BARTHOLOMEW, a citizen of the United States, residing at Chicago, in the county of Cook and State of Illinois, have invented certain new and useful Improvements in Centrifugal Extractors, of which the following is a specification.

My invention relates in general to laundry machinery, and more particularly to centrifugal extractors.

In order that the rapidly revolving basket of a centrifugal extractor may be prevented from injuring the operator, interlocking or connecting mechanism between the power controller and the extractor cover have been provided, which either automatically cut off the driving power when the cover is opened, or prevent the opening of the cover until after the controller has been actuated to discontinue the driving power. Such devices are, however, open to the serious objection that they afford no protection while the basket continues to revolve by momentum after the driving power has been disconnected, as the cover may then be raised and afford an opportunity for the operator to carelessly place his or her hands in the extractor with the resulting danger of injury.

The primary object of my invention is to provide a centrifugal extractor in which the cover will be automatically securely locked in closed position until the basket has ceased to revolve.

A further object of my invention is to provide a centrifugal extractor, in which the driving power cannot be applied to rotate the basket until the cover is closed, and in which the cover will be automatically locked in closed position as long as the basket continues to revolve.

A still further object of my invention is to provide the cover of a centrifugal extractor with a lock, which will be automatically actuated when the power is applied to securely retain the cover in closed position, and which will be automatically held in such locked position while the basket continues to revolve after the power has been disconnected.

My invention will be more fully disclosed

hereinafter with reference to the accompanying drawings, in which the same is illustrated as embodied in a convenient and practical form, and in which—

Figure 1 is a side elevational view, a portion of the casing and basket being broken away; Fig. 2, a plan view with the cover closed and locked; Fig. 3, a detail elevational view of the hasp of the cover; a portion thereof being broken away; and Fig. 4, a detail elevational view of the coöperating parts of the belt shifter and lock actuating means.

The same reference characters are used in the several figures of the drawings to designate the same parts.

A indicates the casing, or curb, of the extractor which is provided with a supporting base B having a platform b at the bottom thereof, which may be secured to the floor.

C designates the perforated basket within the casing A which is adapted to receive the clothes from which the water is to be extracted.

D designates a shaft which is suitably connected to the basket C to rotate the same.

d indicates a pulley fixed upon the shaft D and around which passes a belt E. The belt E passes around an idler pulley e and thence around a large pulley F fixed upon a counter shaft G. A bracket H is secured to the casing A and is provided with diverging arms in the ends of which the shaft G is journaled.

G' indicates a pulley fixed upon the shaft G, while G² indicates a pulley loosely mounted upon the shaft G.

J indicates the power belt which is adapted to be shifted from the loose pulley to the tight pulley, or vice versa, by suitable belt shifting means.

I have shown in the drawings a belt shifting means comprising a rod K which is mounted to reciprocate in bearings h' and h² projecting upwardly from the bracket H. A sleeve M is secured to the rod K by clamp screw m and carries a pair of curved rods n 100 between which the belt J passes.

L designates a lever for reciprocating the rod K and thereby shifting the belt. This lever is fulcrumed at l upon one end of the

bracket H and is pivotally connected intermediate of its ends to an arm k secured to the adjacent end of the rod K.

O designates a circular plate surrounding 5 the opening through the top of the casing A which is provided with a water guard o.

P designates a cover which is pivoted by hinges p to the plate O and when closed prevents access to the interior of the casing 10 and the basket inclosed therein.

The centrifugal extractor above described does not in itself constitute my invention, but is illustrated and described in order that my invention may be fully disclosed.

15 It will be obvious from the subsequent description that my invention is not limited in its application to a centrifugal extractor of the specific construction above described, but is capable of use in connection with 20 other forms of centrifugal extractors, and similar machines.

Q designates a bracket projecting upwardly from the edge of the cover P at a point adjacent its pivotal support upon the 25 plate O. Pivotally connected to the bracket Q is a rod q which passes through a slot in the water guard o and is provided with an offset portion guided by a bearing r formed upon a bracket R secured to the underlying 30 portion of the bracket H. The position of the bearing r is such with relation to the belt shifting rod K that when the belt is shifted to the tight pulley—as shown in full lines in Fig. 2—the rod K will extend across 35 the path of the rod q and thereby prevent the lifting of the cover, while on the other hand when the belt has been shifted to the loose pulley, the rod K is withdrawn from the path of the rod q, so that the cover may 40 be raised, and when raised, the rod q extends across the path of the belt shifting rod K, thereby preventing the belt from being shifted to the tight pulley.

S designates a hasp pivotally connected 45 by the hinge s to the cover P.

S' designates a spring also secured to the cover P and engaging the hasp S, so as to 50 oscillate the same downwardly into engagement with the outer surface of the casing A. A lug s' projects from the hasp S to the rear of the hinge s to limit the upward movement of the hasp about its hinge and thereby protect the spring S' from being broken. The lower end of the hasp is provided with a chamber S² through the inner 55 wall of which is formed an elongated slot s².

T designates a wing or vane pivotally supported at its upper end by the stub shaft t which extends through a bearing in the 60 casing A, and is provided on its outer end with a latch t' of a size and shape to pass through the slot s² in the inner wall of the chamber S² of the hasp. The vane T is located in the path of the current of air created by the rotation of the basket C.

U designates a curved rod substantially horizontally located upon the wall of the casing A by means of bearings u secured to the inner surface of the casing. The forward end of the curved rod U terminates in close proximity with the adjacent surface of the vane T when the latter is in normal position. The rear end of the rod U is pivotally connected to the end of a crank v formed on the end of a rod V, the latter passing through an opening in the casing A and being rotatably supported by bracket v' secured to the bracket H. The end of the rod V which projects through the bracket v' is provided with a crank V' 75 which projects upwardly into the path of trips W' and W² adjustably secured to the under surface of the sleeve M of the belt shifter by means of screws w passing through elongated slots in the overlapping horizontal portions of the trips.

The operation of my improved centrifugal extractor is as follows: After the clothes from which the water is to be extracted have been placed in the perforated basket C, the 90 cover P is closed which withdraws the rod q from the path of the rod K and permits the belt shifting lever L to be moved from the dotted position shown in Fig. 2 to its full line position, thereby shifting the belt 95 J from the loose pulley G² to the pulley G' which is tight upon the shaft G. The shaft G is consequently rotated, which drives the belt E and rotates the spindle D and with it the basket C.

When the cover P is closed, the spring S' forces the lower chambered end of the hasp over the latch t', the latter passing through the slot s² into the chamber S². The movement of the rod K in shifting the belt to the 105 tight pulley causes the trip W² to engage the crank arm V' of the rod V, thereby oscillating the same and through the pivotal connection of the crank arm v on the inner end thereof with the curved rod U 110 reciprocating the latter so that its forward end engages the vane T and oscillates it to the position shown at the left in Fig. 3. This movement of the vane rotates the latch t' within the chamber S² of the hasp, so that 115 the latch is out of register with the slot s², thereby positively locking the cover in closed position immediately upon the shifting of the belt to the tight pulley.

The rotation of the basket C creates a current of air on the outside thereof in the direction in which the basket rotates. The vane T is located in the path of this current of air and is held by it in the oscillated position shown at the left in Fig. 3, thereby retaining the latch in locked engagement with the hasp as long as the basket continues to rotate, even though the driving power has been disconnected from the basket through the shifting of the belt to the loose pulley.

When the rotation of the basket ceases, and the current of air which it creates consequently is discontinued, the vane T oscillates by gravity to a substantially vertical position, as shown at the right of Fig. 3, thereby bringing the latch t into registry with the slot s², so that the hasp may be swung about its pivot out of engagement with the latch and the cover lifted to its open position. It will be observed that the shifting of the belt to the loose pulley causes the trip W' to engage the crank arm V', as will be evident from Fig. 4, thereby reciprocating the rod U out of contact with the vane, so that it will fall by gravity into a vertical position when the current of air is discontinued. The lifting of the cover projects the rod q into the path of the rod K, thereby preventing the shifting of the belt to the tight pulley until the cover has been again closed.

From the foregoing description, it will be observed that I have invented improvements in centrifugal extractors by means of which their operation is rendered at all times entirely safe, as the cover is positively locked in closed position, not only during the connection of the driving power with the basket, but during the rotation of the basket by momentum after the discontinuance of the application of power to the basket. It will be further observed that it is impossible for the operator to apply driving power to the basket until the cover has first been closed, and that immediately upon the connection of the driving means with the basket, the cover will be positively locked closed, and will be automatically held in its locked closed position after the disconnection of the driving means from the basket until the rotation of the basket ceases. The hands of the operator cannot, therefore, be inserted in the extractor while the basket is in motion.

While I have described more or less in detail the specific form in which I have illustrated my invention as embodied, yet I do not wish to be understood as limiting myself thereto, as I contemplate changes in form, proportion of parts, and substitution of equivalents, as circumstances may require, or as may be deemed expedient, and while in the annexed claims my invention is defined as relating to centrifugal extractors, yet I do not wish to be thereby understood as excluding the use of my invention for any analogous purposes for which it may be adapted.

I claim:

1. In a centrifugal extractor, the combination with a casing, of a rotary basket within said casing, means for driving the basket, a cover for closing said casing, means for automatically locking said cover in closed position upon the connection of the driving means with the basket, and means for auto-

matically retaining said cover locked in closed position during the rotation of the basket.

2. In a centrifugal extractor, the combination with a casing, of a rotary basket within said casing, means for controlling the application of power to said basket, interlocking connections between said cover and controlling means for preventing the application of power to the basket until the cover is closed, means for automatically locking said cover in closed position upon the application of power to said basket, and means for automatically retaining the cover locked in closed position during the rotation of the basket. 70 75 80

3. In a centrifugal extractor, the combination with a casing, of a rotary basket within said casing, means for controlling the application of power to said basket, a lock for retaining the cover in closed position, means 85 operated by said controlling means for actuating the lock when the power is applied to the basket, and means for automatically actuating said lock to retain the cover in closed position while the basket continues to 90 rotate after the discontinuance of the application of power to the basket.

4. In a centrifugal extractor, the combination with a casing, of a rotary basket within said casing, means for controlling the application of power to said basket, interlocking connections between said cover and controlling means for preventing the application of power to the basket until the cover is closed, a lock for retaining said cover in closed position, means 95 operated by said controlling means for actuating said lock when power is applied to said basket, and means for automatically actuating said lock to retain said cover in closed position during the rotation of said basket after the discontinuance of the application of power thereto. 100 105

5. In a centrifugal extractor, the combination with a casing, of a rotary basket within said casing, means for controlling the application of power to said basket, a lock for retaining the cover in closed position, means operated by said controlling means for actuating the lock when the power is applied to the basket, and a vane located in the path of the air current generated by the rotation of said basket operatively connected to said lock to actuate the same to retain said cover in closed position. 110 115

6. In a centrifugal extractor, the combination with a casing, of a rotary basket within said casing, means for controlling the application of power to said basket, a cover for closing said casing, locking means actuated by the air current generated by the rotation of said basket for retaining said cover in closed position, a reciprocating rod engaging said locking means to actuate the same, and means operated by said controlling means for reciprocating said rod to actuate said 120 125 130

locking means when power is applied to said basket.

7. In a centrifugal extractor, the combination with a casing, of a rotary basket within said casing, a cover for closing said casing, a reciprocating belt shifting rod, a lock for said cover, and means actuated by said belt shifting rod when moved to shift the belt to the tight pulley for operating said lock to 10 retain said cover in closed position, said

means permitting the operation of said lock to allow the lifting of said cover when moved to shift the belt to the loose pulley.

In testimony whereof, I have subscribed my name.

WILLIAM BARTHOLOMEW.
